UNITED STATES PATENT OFFICE.

FRANKLIN J. DRAKE, OF BOSTON, MASSACHUSETTS, ASSIGNOR TO THE
POPE MANUFACTURING COMPANY, OF HARTFORD, CONNECTICUT.

VELOCIPED-E-SADDLE.

SPECIFICATION forming part of Letters Patent No. 319,470, dated June 9, 1885.

Application filed April 9, 1885. (No model.)

To all whom it may concern:

Be it known that I, FRANKLIN J. DRAKE, a lieutenant in the United States Navy, at present residing in Boston, Massachusetts, have 5 invented certain new and useful Improvements in Velocipede-Saddles, of which the following is a specification.

My improvements relate more particularly to that part or combination of parts in such 10 saddles connecting them with the spring or frame of the velocipede, and are shown as applied in one form to the bicycle-saddle in the annexed drawings, in which—

Figure 1 shows in bottom plan a bicycle 15 spring and saddle with my improvements applied in one form. Fig. 2 shows a front end view of the same. Fig. 3 shows a section of the same, and Figs. 4 and 5 show parts of the same in detail.

20 A is a saddle-supporting plate or frame, and A' is the flexible portion of the seat. B is a saddle-spring. C is a plate or clamp, which I preferably make, for lightness, steadiness, and effectiveness, forked or Y-shaped 25 with the arms C' C', on which are formed lugs c c for hinges, and at the other end of which is an opening, C^o, to admit the folding of it down upon a bolt, and I also, preferably, make it serrated or notched on the side which is to 30 come in contact with the spring. D is a clamp-lug, which may either be formed with or upon the supporting-plate A, or may be attached thereto by means of rivets or a bolt passing through the hole d', and which also bears the 35 projections d d, to which the clamp C is hinged. D' and H are bolts through the supporting-plate A, and upon the bolt D' is the hinge-lug D. When this lug is made a part of the plate

A, the bolt D' is of course unnecessary. Upon the bolt H is operated the thumb-nut E. I place a leather strip, a, upon the under side of the support A, so as to come between it and the added metallic parts, to operate as a washer. It is obvious that the clamp C may be made plain or single instead of forked, as 45 shown. When the saddle is in position and fastened upon the spring, as shown in the drawings, and it is desired to remove it, first the thumb-nut E is removed and the end C^o of the clamp C is released and depressed away 50 from the spring B, and the saddle is easily removed. To replace it, it is put in the desired position, the clamp C folded down against the spring, the nut E replaced upon the bolt H and turned up tightly. This contrivance 55 makes a simple and effective attachment for the saddle to the spring, and has the advantages of allowing the saddle to be easily placed upon or removed from the spring or adjusted to positions, and of giving, by reason of the lever- 60 age, a better pressure upon the bottom side of the spring, and it avoids the necessity of having to remove two nuts from their bolts in order to take the saddle off, as is the case with the rude clamp in common use on bicycle- 65 saddles.

I claim as new and of my invention—

The combination, in a velocipede-saddle, of a supporting-plate, A, a hinge-lug, D d d, with bolt D', a hinged clamp, C, with parts c c', 70 bolt H, and nut E, or their equivalents, constructed to operate essentially as set forth.

F. J. DRAKE.
